(57) CLAIM

The ornamental design for a football bag, as shown and described.

DESCRIPTION

FIG. 1 is a front perspective view of a football bag, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof; and,

FIG. 8 is a bottom view thereof.

The broken lines in the drawings illustrate the portions of the football bag, which form no part of the claimed design.

The broken lines representing stitching are part of the claimed design.

1 Claim, 8 Drawing Sheets
